VACUUM SYSTEM OF CONTROL FOR DIRIGIBLE BODIES

Application filed September 8, 1920. Serial No. 409,031.

Some of the objects of the present invention are to provide a vacuum system for controlling a dirigible body from a distance in response to radiant energy or other impulses; 5 to provide means for steering a dirigible body by a vacuum system arranged to operate automatically or to be operated at will from a distance; to provide a vacuum system of control for dirigible bodies which is actuated 10 by automatic operating means and means responsive to impulses of radiant energy, combined with a selecting mechanism whereby one or the other of the actuating means is rendered effective for control purposes; 15 and to provide other improvements as will hereinafter appear.

In the accompanying drawings, Fig. 1 represents diagrammatically one form of the present invention in vacuum system of control; Fig. 2 represents a side elevation of a part of the mechanism shown in Fig. 1; Fig. 20 3 is a side elevation of another part of the mechanism shown in Fig. 1; Fig. 4 represents a top plan of the mechanism shown in Fig. 25 3; Fig. 5 represents a section on line 5-5 of Fig. 4; and Fig. 6 represents a section on line 6-6 of Fig. 4.

Referring to the drawings, one embodiment of the present invention comprises a 30 steering mechanism 10; apparatus for producing a vacuum 11; a stabilizing device 12 which normally controls the steering mechanism 10; a selector mechanism 13 which connects or disconnects the stabilizing device 12 35 from the steering means 10 and also operates directly upon the steering means 10; and an energy receiving system 14. The details of the energy receiving system are not shown in the drawings but may be of any desired construction, for instance of well known construction adapted to receive radiant energy and operate suitable control devices, such as a relay 15.

For the purpose of controlling the direction of movement of the dirigible body, the steering mechanism 10 comprises a rudder 20 arranged to oscillate about a substantially vertical axis 21 fixed with respect to the moving body. Rigidly secured to the rudder 20 50 are two arms 23 and 24, the former being con-

nected by a cable 25 to one side of a bellows device 26, which comprises a base 27 and a rocking member 28 pivoted to a base 29. The other side of the rocking member 28 is connected by a cable 31 to the arm 24. When the 55 rocking member 28 is in mid position, as shown in Fig. 1, the rudder 20 is also in mid position. The lower side of the bellows 26 is connected by a pipe 33 to the receiver 34 of the vacuum producing device 11. A centrifugal blower or other suitable means 35 is provided which maintains a suitable vacuum in the receiver 34 and is driven by any suitable means. The upper side of the bellows 26 is connected by pipe 37 to pipe 33. The 60 upper side of the bellows 26 is separated from the lower side of the bellows so that there is no internal communication between these two sides, and the two sides of the bellows thus constitute in substance two pneumatic devices. 70

For automatically controlling the steering of the body, the stabilizing means 12 is provided comprising a gyroscope, or other suitable direction maintaining device 40 including a rotor 40' mounted in gimbal rings 41 and 42 to rotate about a normally horizontal axis. The outer gimbal ring 42 is supported at its top by a shaft 43 which has a bearing in a frame 44, and the lower part of 75 the gimbal ring 42 is supported on a shaft 46 which has a bearing in a frame 47. Loosely mounted upon the shaft 46 is a member 50 provided with suitable openings 51 and 52 which are connected respectively to flexible tubes 53 and 54. Rigidly secured to the shaft 46 is a semi-circular member 56 which slides over the member 50 without actually touching it. When the arm 50 and the gyroscope 40 are in central position the ends of 80 the circular member 56 just cover the ports 51 and 52. One side of the member 50 is connected by a cable 60 to the arm 23 and the other side of the member 50 is connected by a cable 61 to the arm 24. The gimbal ring 41 is provided with a rod like extension 64 rigid therewith which co-operates with a cone shaped member 65, this member being carried on one side 66 of a bellows 67. The other side 68 of the bellows 67 is supported by an 85 90 95 100

arm 69 extending from the frame 47. The bellows 67 is provided with compressional springs 72 which tend to hold it in open position. The bellows 67 is connected by a pipe 75 to the receiver 34 of the vacuum producing device 11, and the cone is so constructed that when the bellows 67 is in its open position the gyroscope 40 will be centralized by means of the rod 64.

5 In order to selectively control the system, the selector device 13 comprises two circular disks 80 and 81 supported on a shaft 83, the disk 81 being rigidly secured to the shaft 83, while the disk 80 is rotatably mounted thereon but is held from rotation with respect to the frame 85 by means of a pin 86 which is rigidly secured to the frame 85 and enters a hole 87 in the disk 80, thereby preventing it from being rotated. The disk 80 is provided with seven openings 87, 91, 92, 93, 94, 95, and 96. The opening 92 is connected by a pipe 100 to the bellows 67. The openings 93 and 95 are respectively connected to the pipes 53 and 54. The opening 94 is connected by a 10 pipe 101 to the lower side of the bellows 26 and the opening 96 is connected by a pipe 102 to the upper side of the bellows 26. The disk 81 is provided with six internal radial grooves 105, 106, 107, 108, 109 and 110 disposed at 60° intervals and three external radial grooves 113, 114 and 115 disposed at 120° intervals as shown in Fig. 5. To the shaft 83 is rigidly secured a toothed ratchet 120 which 15 co-operates with a pawl 121 held in engagement therewith by means of a spring 122. The pawl 121 is pivotally connected to member 123 which at one end has a projecting rod 124 provided with a thread upon which a nut 125 moves, and member 123 is held in the 20 position shown in Fig. 3 by means of spring 127 and is prevented from rotating by the member 128. A cap screw 130 is threaded into the projection 131 of the frame 85, its lower end engaging the pawl 121 when the 25 member 123 is in its outermost position as shown in Fig. 3, thus holding the pawl 121 rigidly against the ratchet 120 and preventing the ratchet from over-running its position. A locking nut 132 is provided to hold 30 the cap screw 130 in any desired position. A click-pawl 135 is pivoted at 136 to the frame 85 and is held in engagement with the ratchet 120 by means of a spring 137. This prevents the ratchet 120 from moving backwards. 35 The right hand end of the member 123, as viewed in Fig. 3 is formed into a sleeve 140 into which is screwed a plunger 141 of a solenoid 142. Upon the threaded portion of the plunger 141 is provided a stop nut 143 and a 40 locking nut 144 to limit the stroke of the plunger 141. The solenoid 142 is composed of an outer casing of magnet iron 145 with end pieces of like material 146 and 147. The plunger 141 reciprocates in a brass tube 149, 45 in the right hand end of which is positioned

a stationary core of magnet iron 150. The winding for the solenoid is shown at 151. One side of this winding is connected by a conductor 155 to a contact point 156 which at times engages with an armature 157 of the electromagnet 15. This armature is held in open position by means of a spring 158 and is connected by a conductor 159 to one side of a battery 160, the other side of this battery is connected by a conductor 161 to the other side 75 of the winding 151 of the solenoid 142. The electromagnet 15 is connected by two conductors 164 and 165 to the energy receiving system 14. This system is provided with an antenna 166 and a suitable ground 167.

80 In the operation of the improved system, the rudder 20 is held in the position shown in Fig. 1 by the bellows 26, as air is exhausted equally on either side of this bellows by means of the vacuum producing means 11, and the bellows 67 is deflated, as shown in Fig. 1, as the air is withdrawn from it by means of pipe 75 leading to the vacuum producing means 11. If the dirigible body upon which it is mounted deviates to the right from the pre-determined course as set by the gyroscope 40, the gimbal ring 42 will be rotated in a counter-clockwise direction with respect to the dirigible body, as seen in Fig. 1, and the semi-circular member 56 will uncover the port 52, 95 thus allowing air to enter through port 52 into pipe 54 where it proceeds to the opening 95 in the disk 80, thence through groove 106 to opening 96, thence through pipe 102 to the upper side of the bellows 26, thus breaking the 100 vacuum on this side of the bellows. The rocking member 28 is therefore rotated in a clockwise direction as seen in Fig. 1 for the vacuum is therefore only operating in the lower part which collapses under atmospheric pressure. The rudder is therefore rotated in a clockwise manner, or to the left, by means of cables 105 25 and 31. This causes the movable body to be steered to the left. The cables 60 and 61 cause the member 50 to rotate in a counter-clock-wise direction, as viewed in Fig. 1, until the port 52 is again closed by the semi-circular member 56. The rudder will therefore be turned through an angle which is proportional to the angle through which the 110 movable body has been deviated from its pre-determined course. The rudder being to the left the movable body is therefore returned to the course set by the gyroscope 40 and the rudder is at all times in position proportionate to the amount the movable body is off its 115 predetermined course. Should the movable body deviate to the left a similar action will take place, air entering the port 51, passing through the pipe 53, groove 109, pipe 101 to the lower side of the bellows 26 thus turning the rudder 20 to the right to return the movable body to its predetermined course.

120 If it is now desired to steer the movable body to the right an impulse of radiant ener- 130

gy is sent which being received by the antenna 166 operates the energy receiving mechanisms 14, thereby energizing the electromagnet 15 which closes the circuit of solenoid 142. As soon as the solenoid 142 is energized, the plunger 141 is moved to the right as viewed in Fig. 4 thus moving the member 123 to the right carrying the pawl 121 with it which moves over the ratchet 120 without turning it. The spring 127 is thereby compressed. As soon as an impulse of radiant energy ceases and the magnet 15 is de-energized the circuit through the solenoid 142 will be broken thus allowing the plunger 141 and the member 123 to be moved to the left (as viewed in Figs. 3 and 4) under the action of the spring 127. The pawl 121 being in engagement with the ratchet 120 rotates this ratchet and with it the shaft 83 through one-twelfth of a revolution until the pawl 121 is stopped by the cap screw 130. The ratchet 120 will be held in this position by means of the click pawl 135. The disk 81 being secured to shaft 83 will be rotated through one-twelfth of a revolution thereby moving the groove 110 into alignment with the ports 91 and 92, and blanking off ports 93, 95 and 96 the first two of which are connected to the stabilizing means 12, thus rendering the same inoperative. Groove 115 also moves into operative relation to port 94. This allows air to enter through the port 91, groove 110, port 92, pipe 100 to the bellows 67, thus breaking the vacuum in this bellows which is expanded under the action of the springs 72. The cone 65 will therefore be moved to the left as seen in Fig. 2, and will therefore engage with the rod 64, thus centralizing the gyroscope 40 and holding it central as long as the disk 81 is in this position. The gyroscope is therefore inoperative to control the dirigible body because the pipes 53 and 54 are no longer in communication with the pipes 101 and 102. Air is also admitted through groove 115 to port 94 thence through the pipe 101 to the lower side of the bellows 26 thus breaking the vacuum in this side and allowing the rocking member 28 to rotate in a counter clock-wise direction as seen in Fig. 1 thus turning the rudder 20 to the right to steer the dirigible body to the right. The movable body will continue to move to the right under the action of the rudder 20 as long as the disk 81 is in this position.

If it is now desired to cause the movable body to again be put under control of the stabilizing means 12, another impulse of radiant energy is sent, which being received by the antenna 166 energizes the solenoid 142 thus turning the shaft 83, and therefore the disk 81, through one-twelfth of a revolution as previously described. This brings the groove 108 into alignment with the ports 93 and 94 and the groove 105 into alignment with the ports 95 and 96. The port 92 is blanked off and therefore the bellows 67 is deflated under the action of the vacuum producing means 11. This causes the cone 65 to be moved to the right and out of engagement with the rod 64, thus allowing the gyroscope 40 to be free in space again. The pipes 53 and 54 will therefore be again connected to the respective pipes 101 and 102, thus allowing the stabilizing means 12 to control the rudder 20 as already fully described.

If it is desired to steer the movable body to the left another impulse of radiant energy is sent which turns the disk 81 through an additional one-twelfth of a revolution. This allows air to enter pipe 100 thus centralizing the gyroscope 40, the pipes 53 and 54 are disconnected and air is allowed to enter the pipe 102 through groove 113, which breaks the vacuum in the upper part of bellows 26, thus turning the rudder 20 to the left to cause the dirigible body to be steered in that direction. Thus by sending a suitable number of impulses the dirigible body may be steered either to the right or the left as desired, or put under the control of the stabilizing means.

Having now fully described our invention, what we claim is:—

1. In a control system for dirigible bodies, the combination of a movable body, steering means therefor, a receiving device responsive to impulses of radiant energy, means including a vacuum system controlled by said receiving device for operating said steering means, means for controlling said vacuum system independently of said receiving device and means controlled by said vacuum system for rendering said independent means inoperative.
2. In a control system for dirigible bodies, the combination of a movable body, steering means therefore, a vacuum operated mechanism for operating said steering means, a stabilizing device, a receiving device responsive to impulses of radiant energy, a selector for automatically connecting either of said devices with said vacuum operated mechanism and for automatically restoring said stabilizing device to a predetermined position.
3. In a control system for dirigible bodies, the combination of a movable body, steering means therefor, a vacuum operated mechanism for operating said steering means, a stabilizing device arranged to control said vacuum mechanism to maintain said body upon a predetermined course, and means operated by radiant energy for restoring said stabilizing device to a predetermined position and placing said vacuum system under control for operation from a distance.
4. In a control system for dirigible bodies, the combination of a movable body, steering means therefor, a vacuum operated mechanism for operating said steering means, auto-

matic means for actuating said vacuum operated mechanism, means controlled by radiant energy for selectively actuating said vacuum mechanism, and means controlled by 5 said vacuum operated mechanism for rendering said automatic means inoperative.

5. In a control system for dirigible bodies, the combination of a movable body, steering means therefor, a vacuum operated mechanism for operating said steering means, automatic means for actuating said vacuum operated mechanism, means responsive to radiant energy and including a selective valve for actuating said vacuum mechanism 15 in a predetermined manner, including means for restoring such automatic means to a predetermined position.

6. The combination with a dirigible body, of an element carried thereby and movable 20 with respect thereto to automatically rotate said body about a given axis and means for moving said element with respect to said body including a pneumatic device, means normally acting to evacuate said device, and 25 means responsive to radiant energy for selectively admitting a fluid under pressure to said pneumatic device to cause said device to actuate said element, and including means 30 for disabling said automatic rotating means.

7. The combination with a dirigible body, of means carried thereby for steering said body either in one direction or a different direction, a vacuum system arranged to control said steering means, a stabilizing means 35 normally acting through said vacuum system to stabilize said steering means, a vacuum system arranged to render said stabilizing means either effective or non-effective 40 to control said steering means and to restore said stabilizing means to predetermined position and an element movable to control both of said vacuum systems.

8. The combination with a dirigible body, of means carried thereby for steering said body either in one direction or a different direction, a vacuum system arranged to control said steering means, stabilizing means normally acting through said vacuum system to stabilize said steering means, a vacuum system arranged to render said stabilizing means either effective or non-effective 55 to control said steering means and to restore said stabilizing means to predetermined position and an element movable step by step through a plurality of steps in one direction to control both of said vacuum systems.

9. The combination with a dirigible body, of means carried thereby for steering said body either in one direction or a different direction, a vacuum system arranged to control said steering means, stabilizing means normally acting through said vacuum system to stabilize said steering means, a vacu-

um system arranged to render said stabilizing means either effective or non-effective to control said steering means and to restore said stabilizing means to predetermined position, and an element rotatable step by step 70 through a plurality of steps in one direction to control both of said vacuum systems.

10. The combination with a dirigible body, of means carried thereby for steering said body either in one direction or a different 75 direction, a vacuum system arranged to control said steering means, stabilizing means normally acting through said vacuum system to stabilize said steering means, a vacuum system arranged to render said stabilizing means either effective or non-effective to control said steering means and to restore said stabilizing means to predetermined position and means for selectively controlling both of 80 said vacuum systems including a member provided with a plurality of ports and a second member relatively movable with respect to said first mentioned member and provided with a plurality of recesses arranged to cooperate with said ports.
